*Fig. 7.**Fig. 8.*FIG. 1 is a front perspective view taken from the top and right side of a lavatory embodying my new design;

FIG. 2 is a top plan view thereof;

FIG. 3 is a front elevational view thereof;

FIG. 4 is a left side elevational view thereof;

FIG. 5 is a vertical sectional view taken transversely through the center of FIG. 1;

FIG. 6 is a front perspective view of a modified form of the lavatory shown in FIGS. 1-5;

FIG. 7 is a top plan view thereof;

FIG. 8 is a front elevational view thereof;

FIG. 9 is a left side elevational view thereof; and

FIG. 10 is a vertical sectional view taken transversely through the center thereof.

The dominant features of my design reside in the portions shown in full lines.

This application is a continuation of my co-pending applications Serial Nos. D-59,057 and D-59,058, both filed on January 15, 1960, now abandoned.

I claim:

The ornamental design for a lavatory, as shown and described.
